[57] CLAIM

The ornamental design for a keyboard, as shown and described.

DESCRIPTION

FIG. 1 is a front elevational view of the keyboard of the present invention;

FIG. 2 is a rear elevational view of the keyboard of FIG. 1; FIG. 3 is a left side elevational view of the keyboard of FIG. 1;

FIG. 4 is a right side elevational view of the keyboard of FIG. 1;

FIG. 5 is a top plan view of the keyboard of FIG. 1; and, FIG. 6 is a bottom plan view of the keyboard of FIG. 1. The cord is shown broken away in the views and is understood to represent an indeterminate length.
